UNITED STATES PATENT OFFICE.

SIGURD ANDERSON, OF LEAVENWORTH, KANSAS.

BASEBALL GAME.

Application filed November 14, 1927 Serial No. 233 104.

My invention relates to an indoor baseball game which is played with a board and a number of cards, and one object is to provide a game of this character which may be 5 played with scores similar to the regular game of baseball as played by major league baseball teams.

A further object is to provide a game which will resemble to a large extent the 10 actual game of baseball, with all the thrills and unexpected happenings to be had in a regular baseball game.

The complete game consists of a deck of cards and a board with indicators, which 15 latter are used in keeping track of the game so that the particular situation at the time of playing each card can be determined. A plurality of cards, preferably about one hundred, are used and each card indicates one or 20 more of the numerous situations which arise in an actual ball game.

In order that the invention may be fully understood, reference will now be had to the accompanying drawings, in which:

25 Fig. 1 is a plan view of the board employed in carrying out the invention.

Fig. 2 is a plan view similar to Fig. 1, with the upper sheet of member of the board removed.

30 Fig. 3 is a longitudinal section on line 3—3 of Fig. 1.

Fig. 4 is an enlarged broken section on line 4—4 of Fig. 1.

Fig. 5 is a detail of one of a number of 35 segments employed in carrying out the invention.

Fig. 6 is an enlarged fragmentary detail of the lower portion of the sheet or member disclosed by Fig. 2.

40 Fig. 7 is a detail of one of a plurality of devices representing two opposing ball teams.

Figs. 8 and 9 are plan views of some of the cards employed in carrying out the invention.

45 Referring in detail to the different parts, 2 designates in general what I have termed a board. Said board comprises three members, to wit: A bottom member 4, an intermediate member 6, and a top member 8. The bottom member 4 may consist of wood or other suitable material and is surrounded by a marginal flange 10 which acts as a guide for the intermediate member 6 and a 50 support for the top member 8. The bottom

member 4 is also provided with two upwardly converging grooves 12 and 14, representing the "dugouts" for the respective teams and containing step-shaped holders 16 and 18 for holding devices 20 and 22, 60 respectively. Said devices 20 and 22 represent the opposing teams and are marked to indicate pitcher, catcher, first baseman, etc., as more clearly shown by Fig. 7, which shows a device bearing the inscription "Second 65 baseman". The devices 20 and 22 are arranged in the respective dugouts in the batting order of the ball teams which they represent.

Segmental indicators 24, 26, 28 and 30 are 70 operably mounted at the respective corners of the bottom member 4, for keeping track of the game. The indicator 24 contains numerals 0 to 3, inclusive for designating the "outs"; the indicator 26 contains numerals 75 0 to 5, inclusive, for indicating the "runs"; the indicator 28 contains numerals 0 to 4, inclusive, for indicating the "balls"; and the indicator 30 contains numerals 0 to 3, inclusive, for indicating the number of 80 "strikes". The indicators 24, 26, 28 and 30 are operably mounted upon suitable elements such as screws 32, which also serve to hold the top member 8 upon the bottom member 4.

The intermediate member 6 consists of 85 suitable material such, for instance, as a sheet of cardboard and is arranged for longitudinal slidable movement between the bottom member 4 and the top member 8, as indicated by the full and dotted lines Fig. 90 2. The intermediate member 6 is cut out at the corners as shown at 32^a for the reception and operation of the indicators 24, 26, 28 and 30, and is also provided with two upwardly converging slots 34 and 36 for 95 registry with the grooves 12 and 14, respectively. As shown by Fig. 2, the slot 36 is slightly higher than the slot 34 so that when the intermediate member 6 is in raised position as shown by full lines it will cover 100 the groove 14 while the slot 34 will register with the groove 12 and disclose the devices 20, and when said intermediate member 6 is pulled downwardly to the position indicated by the dotted lines Fig. 2, it will cover 105 the groove 12 and uncover the groove 14 and the devices 22 by carrying the slot 36 into registry with the latter groove.

In addition to the foregoing, the intermediate member 6 contains pictorial repre- 110

sentations of the two opposing teams and their coaches arranged in approximately their playing positions, one of said teams being designated by the numeral 38 and the other by the numeral 40, and one set of coaches by the numeral 42 and the other by the numeral 44.

The top member 8 of the board may be made of the same kind of material as the intermediate member 6 and, as shown by Fig. 1, contains a representation of the ball park showing the grand stand 46 and 47, the diamond 52 for the pitcher, catcher and the infielders, the outfield 54 for the outfielders and boxes 56 and 58 for the coaches.

The top member 8 also has two upwardly converging slots 48 and 50 which are directly above the grooves 12 and 14, respectively, in the bottom member 4 for exposing the devices 20 and 22 as they are alternately uncovered by the intermediate member 6. Openings 62 and 63 are formed in the top member 8 through which the teams 38 and 40 and the coaches 42 and 44, respectively, are alternately displayed as the intermediate member 6 is shifted up or down. The top member 8 also has circles or other suitable indicia 41 and 43, representing, respectively, the umpire in chief and the field umpire.

Arcuate slots 64, 66, 68 and 70 are formed in the top member 8 to give access to finger holes 72, 74, 76 and 78 in the indicators 24, 26, 28 and 30, respectively, so that a finger may be inserted in any of said holes preparatory to shifting the respective indicators to carry the numerals thereon beneath openings 80, 82, 84 and 86 formed in the top member 8 and designated, "outs", "runs", "balls" and "strikes", respectively. A slot 88 is also formed in the central lower portion of the top member 8 to give access to a finger hole 90 formed in the intermediate member 6, so that the latter may be readily shifted to the full or dotted line positions disclosed by Fig. 2. The names of the opposing teams are also inscribed upon the intermediate member 6, one of said names with the phrase "At bat", being located just above the finger hole 90, and the other name with the phrase being located just below said finger hole 90, as shown by Fig. 6.

In order that the finger may be passed through the finger holes 72, 74, 76 and 78 to better engage the indicators 24, 26, 28 and 30 for the purpose of shifting the latter, I provide the bottom member 4 with arcuate slots 92 which register with the arcuate slots 64, 66, 68 and 70. The bottom member 4 is also provided with a slot 94 which registers with the slot 88, so that the finger may be passed through the finger hole 90 preparatory to shifting the intermediate member 6 up or down.

In order that the two teams and their coaches may be readily distinguished from

each, one may be provided with red stockings and the other with blue stockings and their dugouts 12 and 14 may be designated "Sed Sox" and "Blue Sox", respectively. The devices 20 and 22 may also be colored 70 red and blue, respectively.

Any suitable number of cards 98 may be employed in playing the game. Preferably, I prefer to use 100 cards which have suitable inscriptions for indicating the different combinations of plays which may arise in actual ball game. Some of the cards may be duplicates and each bears the representation of a diamond 100 and small circles 102 representing the team in the field. Each 80 card also has dotted lines 104 indicating the course of the ball from the pitcher to the batter and some of the cards also have dotted lines 106 indicating the course of the batted ball, said dotted lines varying on the different cards to indicate the different directions taken by the pitched and batted balls.

The game is best played by two persons or any suitable multiple thereof, and in starting the game each side chooses the team 90 it is to control. It is also decided which team shall go to bat first. If there is an odd party he can shuffle and deal the cards and keep the score on a regular score card.

After shuffling the cards the dealer deals one 95 card at a time to the players, starting in with the player at the left and continuing around until each player has received a hand of six cards. The first player on one side then plays a card face up, choosing one, if in his possession, which will place the batter on one of the bases. The second player who represents the opposing team then plays a card, if in his possession, which will put out the batter or the runner 100 on base. The third player then plays a card, if in his possession, which will advance the batter, after which the fourth player follows the suit of the second player and attempts to put the batter and runners out. 105 In the course of the game it may happen that one of the players will hold a certain card too long to benefit his team on the next play, and which must be played to the benefit of the opposing team, as no player 110 should have any cards left when the next hand of six cards is dealt.

At the start of the game the intermediate member 6 is adjusted to expose at the openings 62 the ball team that first takes the field. 115 Said adjustment of the intermediate member 6 also exposes the devices in the dugout of the team at bat and exposes the name of the latter team at the slot 88. The indicators 24, 26, 28 and 30 are initially adjusted to expose the respective naughts at the openings 80, 82, 84 and 86 and as the first half inning progresses said indicators are adjusted to expose the number of outs, runs, 120 balls and strikes occurring during said first 125

half inning. After the first half inning has been played the intermediate member 6 is adjusted to expose at the openings 62 the team taking the field, the devices representing the team at bat, the name of the team at bat at the slot 88 and the coaches of the team at bat, while the indicators 24, 26, 28 and 30 are adjusted to expose the naughts at the respective openings 80, 82, 84 and 86.

10 While I have shown one form of the invention I reserve all rights to such changes and modifications thereto as properly fall within the spirit and scope of the invention as claimed.

15 Having thus described my invention, what I claim and desire to secure by Letters Patent, is:

1. In a game of the character described, a top member having a representation of a 20 baseball field with openings for displaying baseball teams in their respective playing positions, numeral display openings near its corners and arcuate slots near said numeral display openings; a longitudinally slidable 25 intermediate member underlying said top member and having representations of two opposing baseball teams so arranged that when said intermediate member is moved in one direction one of said teams will appear at 30 the openings in the baseball field and when moved in a reverse direction the opposing team will appear at the last-mentioned openings, said intermediate member being cut out at its corners; elements underlying said top 35 member and arranged at said cut out corners of the intermediate members, said elements bearing numerals for exposure at the numeral display openings and provided with finger holes registering with the respective 40 arcuate slots, and a bottom member underlying said intermediate member and to which said movable elements are pivotally connected.

2. In a game of the character described, a 45 bottom member having two oppositely-disposed dugouts, a set of markers representing a ball team and adapted to be placed in one of said dugouts in the batting order of said team, another set of markers representing an 50 opposing ball team and adapted to be placed in the other dugout in proper batting order, an intermediate member movable upon said bottom member and having representations of two opposing ball teams and two slots one 55 of which uncovers one set of markers when said intermediate member is moved in one direction and the other of which uncovers the other set of markers when the intermediate member is moved in a reverse direction, 60 and a top member having slots which register with the dugouts in the bottom member and a representation of a baseball field with openings for displaying one of the baseball teams when the intermediate member is 65 moved in one direction and the opposing

team when the intermediate member is moved in a reverse direction.

3. In a game of the character described, a bottom member having two oppositely-disposed dugouts, a set of markers representing a ball team and adapted to be placed in one of said dugouts, another set of markers representing an opposing ball team and adapted to be placed in the other dugout, an intermediate member movable upon said bottom member and having two slots one of which uncovers one set of markers when said intermediate member is moved in one direction and the other of which uncovers the other set of markers when the intermediate member is moved in a reverse direction, and a top member having slots which register with said dugouts.

4. In a game of the character described, a bottom member having two oppositely-disposed dugouts, step-shaped holders arranged within said dugouts, a set of markers representing a ball team adapted to be placed in one of said holders, another set of markers representing an opposing ball team and adapted to be placed in a holder of the other dugout, an intermediate member movable upon said bottom member and having two slots one of which uncovers one set of markers when the intermediate member is moved in one direction and the other of which uncovers the other set of markers when said intermediate member is moved in a reverse direction, and a top member having slots which register with said dugouts and a representation of a baseball field over which the markers may be moved and placed upon the different bases of the infield.

5. In a game of the character described, a bottom member having two oppositely-disposed dugouts, a set of markers representing a ball team and adapted to be placed in one of said dugouts in the batting order of said team, another set of markers representing the opposing ball team and adapted to be placed in the other dugout in proper batting order, a second member movable upon said bottom member and having representations of two opposing ball teams and provided with two slots one of which uncovers one set of markers when said second member is moved in one direction and the other of which uncovers the other set of markers when said second member is moved in a reverse direction.

6. In a game of the character described, a bottom member, two sets of markers supported by said bottom member and representing two opposing ball teams, an intermediate member movable upon said bottom member and having representations of two opposing ball teams and provided with two slots one of which uncovers one set of markers when said intermediate member is moved in one direction and the other of

which uncovers the other set of markers when said intermediate member is moved in a reverse direction, a top member having slots with which the first-mentioned slots alternately register when the intermediate member is moved in reverse directions and provided with a representation of a baseball field over which the markers may be moved and placed upon the different bases of the infield, and a number of cards having means

for indicating possible arrangements of the markers on the board, and provided with means for designating a possible play by the batter suitable to the arrangement of the markers on the board, and for indicating 15 the effect of the play on any other player on the bases.

In testimony whereof I affix my signature.

SIGURD ANDERSON.
